ABRASIVE SHEET MATERIAL

Howard G. Bartling, Chicago, and Ellsworth B. Overshiner, Dixon, Ill., assignors, by mesne assignments, to Minnesota Mining & Manufacturing Company, St. Paul, Minn., a corporation of Delaware

Continuation of application Serial No. 335,999, January 29, 1929. This application March 15, 1933, Serial No. 660,890

5 Claims. (Cl. 51—303)

This invention relates to improvements in flexible, abrasive sheet material commonly known in the trade as abrasive paper or cloth, such as sand, flint, emery, garnet and artificial abrasives, and in the method of manufacturing the same, and one of the objects of the invention is to provide an improved abrasive sheet material of superior quality having great flexibility and durability, without possessing any objectionable qualities such as cracking or tearing of the material, and which will be highly resistant to deterioration or wear.

Heretofore abrasive material of this character usually comprises a base of a flexible sheet fabric or paper to which grit or a layer of abrasive particles are applied and secured by means of a binder interposed between the sheet and the abrasive particles, the binder having certain characteristics according to the nature of the work to be performed, that is, for wet or dry work.

This application is a continuation of our application S. N. 335,999 filed January 29, 1929.

With such material considerable difficulty and inconvenience has been experienced as the friction between the sanding element and work causes injury to binder and the abrasive particles quickly become detached. Furthermore, the fabric or paper may quickly wear or become torn. If heavy fabric or paper is employed as a base, the work, and especially the finer or higher grade of work, might be marred, scratched or otherwise injured thereby.

It is one of the objects of the present invention to provide an improved abrasive sheet material in which the bond or binder and the fabric or paper will be dispensed with, and the abrasive material will be attached or secured in position to a flexible body portion by means of the inherent qualities of the material or substance constituting or forming the body portion of the sheet material.

A further object is to provide an improved abrasive element embodying only a flexible body portion and an abrasive element applied and secured thereto or embedded therein without the employment of an adhesive or binding material between the body portion of the element and the abrasive material.

In carrying the invention into operation the body portion of the abrading element is formed of a flexible material such as cellulose or any other suitable substance which initially is preferably in the form of a liquid of any desired consistency, and preferably a plastic material

capable of clinging to a surface while drying, the substance being of such a nature that an abrasive may be applied thereto or mounted thereupon. The substance of which the body portion is composed should also be of such a nature and material that after the solvents have been evaporated it may be stripped or removed from such surface and when removed will be flexible and of any desired thickness with the abrasive firmly attached or secured thereto. The cellulosic material which we may employ may be cellulose nitrate, cellulose xanthogenate or cellulose acetate, all of which are reactive to the normal solvents therefor. If desired, these materials may be reinforced by the addition of various gums or gum resins. The solvents which we may employ may be acetone, with or without a ketone, and any other of the known solvents for these cellulosic materials. These cellulosic materials have the characteristic of relatively rapidly solidifying when formed into a layer, the side of which contacts an adjacent surface as will hereinafter appear, solidifying before the exposed surface.

The liquid is manipulated or formed in any desired or suitable manner into a sheet of any desired length, width and thickness and is subjected to a drying operation preferably so that one side or face thereof will dry more rapidly than the other, and sufficiently to permit the material to be advanced or moved forward, and at the same time leaving the top surface "tacky" or "sticky."

To this surface, before the same becomes dry, is applied in any suitable manner, deposited thereupon, or embedded therein, the abrasive material, preferably in the form of sand, emery, flint or garnet, or like material, or the artificial abrasives which are used in many instances, in preference to the natural abrasives mentioned.

As the material forming the body portion of this product solidifies or dries into the flexible sheet, the grit or abrasive material becomes fastened or secured thereto by the inherent qualities of the material forming the body portion of the element, and the abrading material will be fastened to the body portion more securely than if an adhesive is applied to secure the abrading material to a cloth, paper or other backing.

Furthermore, with the present invention the product consists of but two elements, one of which is a flexible substance, preferably though not necessarily non-metallic, and the other an abrasive material, the two being fastened or se-

cured together without the added use of adhesives, binders or backing.

As the abrasive is applied to the body portion, while the latter is plastic or semi-dry, it will become a part of the flexible body portion as the latter solidifies or hardens through evaporation of the solvents therefrom.

During the operation the material will harden or solidify around the atoms or particles of the abrading material and firmly hold or secure them to the surface of the body portion of the element.

This abrasive sheet may also be produced in another manner as the plastic or semi-plastic body portion may be formed and allowed to become partially or thoroughly dry or solidified, and at a subsequent time apply the abrasive to the surface thereof.

If this latter method is employed, then one face of the body portion thus produced may be dampened with the liquid of the same material as the body portion, or with a solvent in a liquid state so as to render the surface of the body portion "sticky" or "tacky," after which the abrasive material may be deposited upon, applied to or embedded in such surface in any desired manner. A further drying or solidification of the product thus produced will cause the particles of the body to firmly grip around the atoms or particles of the abrasive material.

If desired and in order to reinforce the body portion of the abrading element, a flexible reinforcing element, preferably, although not necessarily non-metallic, may be embedded or molded therein with the body portion of the abrading element formed around or about the same.

The methods disclosed herein for producing an abrasive article of this invention may be carried out by various apparatus and in the figures of the drawing we have illustrated embodiments of apparatus for producing an abrasive article of the character described herein.

In the drawing:

Figure 1 is a diagrammatic view of apparatus for carrying out one of the methods disclosed herein.

Figure 2 is a modified form of the invention and

Figure 3 is a still further modified form.

Referring now to Figure 1, there is provided a carrier or conveyor, preferably of a flexible but stable nature indicated at 5, said carrier having a relatively smooth exposed upper surface 6, to which is applied the cellulosic compound forming the backing of the abrasive article to be produced, the path of the conveyor 5 being changed in direction as indicated at 7 by passing over a suitable roller or over propelling means.

Above the conveyor, and spaced the desired distance therefrom we provide a hopper 8 for binder material which is extended to serve the purpose of the backing herein described. This backing material, preferably of a cellulosic character, is indicated flowing in plastic form from the hopper 8 at 9 into a layer 10 on the conveyor 5.

Owing to the nature of the adhesive employed the back surface thereof in contact with the belt or conveyor 5 has a tendency to solidify or harden more rapidly where it contacts at 12 with said conveyor than at its outer surface 13; the outer surface remains in a plastic or semi-plastic state as the backing material or binder passes beneath the hopper 14, which hopper is adapted to contain a pulverulent abrasive material 15 for

deposition on the backing 10 which abrasive is applied to the plastic surface of the backing 10 to form a layer of abrasive 16.

As the layer or backing 10 having the grit incorporated therein moves along the conveyor 5 by adhesion thereto and approaches the deflected portion 7 of the conveyor, the backing engages a stripping blade 17 positioned so as to have its reduced edge 18 presented tangentially to the conveyor thus stripping the backing and its grit layer from the conveyor.

In order to cause the preliminary setting of the backing or to hasten the setting of the tacky surface of the backing 10, cooling air blasts may be directed against the underside of the conveyor as indicated at 19 and 20, 20.

The air blast delivered from the nozzle 19 is applied before the layer of binder material reaches the point of deposition of the grit and the other air blasts 20 are applied after the binder passes the grit hopper.

It will be understood that the conveyor may be of any desired length depending upon the ingredients employed in the backing layer and the time interval between the deposition of binder and deposition of grit required to produce the desired results. An auxiliary drying nozzle 21 may be provided if desired for hastening setting of the backing at the end of the flight to the conveyor.

Referring now to Figure 2, the assembly here is substantially the same as that shown in Figure 1 and a detailed description of all of the parts thereof is therefore not included. For some purposes it may be desired to allow the backing 10 to become set before receiving the grit, but if this is done as hereinabove explained, the means for supplying a solvent in a liquid state for rendering the exposed surface of the backing 10 tacky may be employed. Such a means is disclosed at 22 and includes a nozzle controlled by valve 23.

Referring now to Figure 3, the apparatus therein disclosed is substantially the same as that shown in either Figure 1 or 2, or both, as may be desired, a conveyor 5a being provided having a divergent portion 1a.

Upon the conveyor 5a is applied a backing or reinforcing element 25 and this element is moved by any suitable means along with the conveyor 5a beneath the binder-containing hopper 26 and the grit-containing hopper 27.

The binder layer of cellulosic material or the like is shown at 28 issuing from the hopper 26 and adapted to receive the grit layer 29 supplied from the hopper 27.

If desired, a process of moistening the exposed surface 30 of the binder layer 28 may be resorted to by the provision of the solvent delivering nozzle 31 shown in dotted lines.

It will be understood that the several forms of the apparatus are purely diagrammatic and may be varied structurally to suit conditions of operation in the course of actual manufacture of the abrasive article.

In any form of the invention the abrading particles become a part of the body portion without the use of added adhesives, sizing or bond of a different material from the body portion and the entire abrading element is formed without a fabric, paper or other backing, and added adhesives as now used on sand papers or abrasive cloths, thereby eliminating sizing the backing or surface of the material.

While the preferred method of producing this

article has been herein described, it is to be understood that various changes may be made in the steps of the process or the mode of producing the same and the body portion and the abrasive particles may be secured together in any suitable manner in which a backing and the provision of a binder or adhesive between the body portion and the abrading particles will be dispensed with.

5 What is claimed as new is:

- 10 1. The method of manufacturing flexible abrasive material which consists in providing a substance in plastic form, then shaping said material by casting and partially solidifying the same progressively from the casting surface and leaving an exposed surface unsolidified, then applying abrasive particles to the unsolidified surface, and then completely solidifying such surface.
- 15 2. The method of manufacturing flexible abrasive material which consists in providing a non-metallic substance in plastic form, then shaping said material by casting and partially solidifying the same progressively from the casting surface and leaving an exposed surface unsolidified, then applying abrasive particles to the unsolidified surface, and then solidifying such surface by evaporating the solvents therefrom, and solidifying the entire article so cast with the abrasive particles in situ.
- 20 3. The method of manufacturing abrading material which consists in casting upon a continuously moving surface a plastic mass from a liquid which adheres to said surface and becomes a flexible substance after evaporation of its sol-

vents, then applying abrasive particles to the exposed face of such substance so cast while said face is still in a plastic state, then evaporating the solvents, the abrading particles being secured to such substance solely by solidifying 5 the adjacent portion of the substance about said particles, and then removing the cast body portion with the abrasive fastened thereto, from the surface upon which the body has been formed.

4. A process for forming an abrasive article 10 which includes as steps thereof, forming a plastic body on a movable conveyor, and causing same to adhere thereto, drying or setting one surface of said body to provide a cast surface while leaving the other surface tacky, applying 15 a layer of abrasive particles to said tacky surface, and then setting the body for retaining the abrasive particles therein and removing said body from the conveyor along the cast surface.

5. The method of producing flexible sheet 20 abrasive material which consists of casting upon a continuously moving supporting surface a plastic mass of liquid consistency in a volatile solvent, which is capable of being converted into 25 a solid flexible mass that will retain abrasive grains embedded in the surface thereof, then applying abrasive grains to the surface of the plastic mass before it becomes too hard to receive said abrasive grains, then hardening the plastic mass by evaporating the solvent, and then 30 removing the hardened plastic mass from the supporting surface.

CERTIFICATE OF CORRECTION.

Patent No. 2,220,140.

November 5, 1940.

HOWARD G. BARTLING, ET AL.

It is hereby certified that error appears in the printed specification of the above numbered patent requiring correction as follows: Page 3, first column, line 18, claim 1, after "face" insert --and the material with the abrasive particles in situ--; and that the said Letters Patent should be read with this correction therein that the same may conform to the record of the case in the Patent Office.

Signed and sealed this 7th day of September, A. D. 1943.

Henry Van Arsdale,
Acting Commissioner of Patents.
